UNITED STATES PATENT OFFICE.

FREDERICK WILL, OF ROCHESTER, NEW YORK, ASSIGNOR TO SILL STOVE WORKS, OF ROCHESTER, NEW YORK, A CORPORATION OF NEW YORK.

WATER-HEATER.

1,242,294.

Specification of Letters Patent.

Patented Oct. 9, 1917.

Application filed August 28, 1916. Serial No. 117,281.

To all whom it may concern:

Be it known that I, FREDERICK WILL, of Rochester, in the county of Monroe and State of New York, have invented certain new and useful Improvements in Water-Heaters; and I do hereby declare the following to be a full, clear, and exact description of the same, reference being had to the accompanying drawings, forming a part of this specification, and to the reference characters marked thereon.

My invention relates to improvements in water heaters and more particularly to the type used in conjunction with cooking stoves and ranges, and has for its object to provide a water heater by means of which water may be heated either by the combustion of fuel in the usual fire box or by a gas flame or other source of heat independent thereof. A further object of the invention is to provide a water heater in which different portions of the heater may be used independently of each other for heating water at different times. A still further object of the invention is to provide a water heater so constructed that expansion and contraction of the parts will not be detrimental to the heater. To these and other ends the invention consists in certain improvements and combinations of parts, all as will be herein-after more fully described, the novel features being pointed out in the claims at the end of the specification.

In the drawings:

Figure 1 is a side elevation of a stove or range in which one embodiment of the invention is shown;

Fig. 2 is a transverse sectional view taken on line *a—a* of Fig. 1;

Fig. 3 is a detail side elevational view showing the manner of mounting the coil pipes which are positioned over the gas burner;

Fig. 4 is a similar view showing the arrangement of the pipes which are adapted to be heated by the burning of coal or wood, and

Fig. 5 is an enlarged detail sectional view through the head showing the application of one set of coils thereto.

Similar reference characters throughout the several views indicate the same parts.

In the construction of stoves or ranges which are provided with water heating apparatus designed to be heated by the burn-

ing of coal or wood, it is found desirable to combine therewith means for heating water by the burning of other combustible materials such as gas and the like, it being understood that at certain seasons of the year it is deemed more convenient, economical and generally satisfactory to employ gas as a heating medium in preference to wood or coal and especially in the heating of water for various purposes in a minimum amount of time. For these reasons I have provided a water heater, a portion of which may be utilized for heating water by the burning of coal or wood and another portion by the burning of gas and the like; no rearrangement of the parts being necessary in changing from one heating medium to another. Referring to the drawings by numerals 10 represents a stove or range of any preferred type provided with a fire-box 11 having the usual grate bars 12. Above the fire-box 11 is a heating chamber 13 from which leads a passage way 14 for carrying off smoke and other products of combustion. One of the walls of the fire-box 11 is formed by a plurality or group of spaced superimposed coils 15, between which are positioned fillers 16 for closing the openings between the coils to prevent the escape of the fuel from the fire-box as well as to prevent air entering therein except through the grate at the bottom thereof. The coils 15 are preferably formed of one piece, the ends of which are suitably connected with the chambers 17 and 18 of a head formed by the plates 19 and 20 rigidly connected as shown in Fig. 5. The plate 20 is provided with a circumferential flange 21 which serves to space said plate from the plate 19. Between the flange 21 and plate 19 is positioned a packing ring 22 adapted to form a water tight joint between said members. The plate 20 is also provided with a centrally positioned transverse member 23 for dividing the head into the separate chambers 17 and 18. Between the member 23 and the plate 19 is positioned a packing strip 24 adapted to form a water tight joint between the chambers. If it is desired to make the head more rigid the same may be cast in one piece with the dividing wall 23 integral therewith without departing from the spirit of the invention. A water supply pipe 25 connects with the chamber 18 through the plate 20. The supply pipe may be connected with any suitable source for

supplying water to the chamber. A discharge pipe 26 leads from the chamber 17 to a tank or other container (not shown) provided for storing hot water adapted to be circulated through the coils 15 when fuel is burned in the fire-box 11. The head formed by the plates 19 and 20 is preferably positioned at the back of the stove 10 in a combustion chamber 27 positioned adjacent the fire-box 11 as shown in Fig. 2. A series or group of coil pipes 28 preferably smaller in diameter and of a greater number than the coils 15, have their lower ends communicating with the chamber 18 and their upper ends with the chamber 17 so that water entering the lower chamber will circulate through the coils into the upper chamber and out through the discharge pipe 26 at the same time that water is circulating through the coils 15 when fuel is being burned in both of the combustion chambers. Beneath the coils 28 is positioned any suitable type of gas burner 29 provided with a mixer 30 adapted to receive gas from a supply pipe 31 through a valve 32 for controlling the supply of gas to the burner. A hinged door 33 is provided to afford access to the chamber 27 and burner 29. Suitable openings 34 and 35 are shown leading to the chamber 27 for furnishing a sufficient supply of air to the burner 29. A damper 36 is positioned at the top of the chamber 27 for discharging therefrom into the chamber 13, the products of combustion accumulating in the chamber. By attaching the groups of coils 15 and 28 to a single rigid head free to move as shown, I overcome the usual trouble experienced in the uneven expansion and contraction of water tube heaters of the spaced or fixed head type. In the present instance the head and coils both are free to move in either direction when expanded and

contracted as the pipes 25 and 26 which support said members are loosely positioned through the back wall of the stove. It will be understood that the two sets of tubes 15 and 28 form independent water circulating mediums which may be heated separately or at the same time by the burning of unrelated supplies of fuel from separate and independent sources.

I claim as my invention:

1. In a water heater, the combination with a fire-box, of a water head, a water circulating medium connected with the head and arranged to be heated by the combustion of fuel in said fire-box, a second water circulating medium connected with the head and a liquid fuel burner arranged to supply heat to the second mentioned medium independently of the first.

2. In a water heater, the combination with a fire-box, of a water head, tubes connected with the head adapted to form a wall of the fire-box, additional tubes connected with the head independent of the first mentioned tubes, and a liquid fuel burner arranged to heat said additional tubes.

3. In a water heater, the combination with a fire-box, of a water head having inlet and outlet chambers formed therein, a water circulating tube having one of its ends connected with the inlet chamber and its other end with the outlet chamber, said tube forming a wall of the fire-box, a plurality of tubes each having one of its ends connected with said inlet chamber and its other end with said outlet chamber, and means independent of the fire-box for heating the last mentioned tubes.

FREDERICK WILL.
